UNITED STATES PATENT OFFICE.

ALFRED O. BRUNNE, OF MERIDEN, CONNECTICUT.

LAMP.

SPECIFICATION forming part of Letters Patent No. 404,162, dated May 28, 1889.

Application filed March 19, 1888. Serial No. 267,595. (No model.)

To all whom it may concern:

Be it known that I, ALFRED O. BRUNNE, of Meriden, in the county of New Haven and State of Connecticut, have invented certain new and useful Improvements in Lamps, of which the following is a specification.

This invention has reference to certain improvements in lamps with a central draft, said improvements being designed with a view to produce the more perfect combustion of the oil by supplying an additional quantity of oxygen to the outer as well as to the inner surface of the same, whereby a whiter flame is produced at a saving of the illuminant.

The invention consists of certain details of construction and combination of parts, which will be fully described hereinafter, and finally pointed out in the claim.

In the accompanying drawings, Figure 1 represents a side elevation of my improved lamp. Fig. 2 is a vertical transverse section of the upper or burner part of the same, drawn on a larger scale. Figs. 3 and 4 are respectively a detail side elevation of the lower part of the interior draft-cone and a horizontal section of the same on the line $x x$, Fig. 4.

Similar letters of reference indicate corresponding parts.

Referring to the drawings, A represents the fount of my improved lamp, which is provided with a central-draft tube, A', and a base, A'', having openings α for admitting the air to the central-draft tube A'. The central-draft tube A' is rigidly secured to the bottom of the lamp-fount, as customary in central-draft lamps of this class. A wick-holding tube, B, is arranged concentrically to the central-draft tube A' and provided with the usual slots or openings, d, for permitting the access of the oil to the wick C, which is interposed between the fixed draft-tube A' and the wick-holding tube B.

To the neck A³ of the fount A is applied, by a bayonet-joint, e, a perforated air-supply cylinder, E, as shown in Fig. 1. The perforated cylinder E is provided with an interior tube, E', that is concentric to the central-draft tube A', and forms with the same, respectively, the outer and inner wick holding and guiding tubes.

The perforated cylinder E is provided with

a series of small perforations, e', and with one or more rows of larger perforations, e'', which latter are arranged, preferably, at the upper 55 or lower edge of the cylinder E, or at one or more intermediate points of the same. The smaller perforations, e', supply a steady quantity of air, while the rows of larger perforations permit the entrance of extra sheets or 60 bodies of air, which are supplied to the outer surface of the flame—one to the base, the other to the upper part of the same. For the purpose of preventing, however, the too abrupt supply of too large a quantity of air to the 65 outer surface of the flame, the chimney-supporting gallery E² at the upper part of the perforated cylinder E is provided with a perforated ring, e³, which is made either of a detachable piece of perforated sheet metal, or 70 integral with the gallery E², as desired.

In the drawings the perforated ring e³ is made of a separate piece of sheet metal and fitted tightly around the outer wick-tube, E', as shown clearly in Fig. 2. The perforated 75 ring e³ serves as a screen for regulating and distributing the air in a uniform manner to the outer surface of the flame and prevents effectually the flickering of the flame, which would take place with a too large and unrestrained 80 supply of air to the outer surface of the flame. The gallery E² is provided with the usual spring-arms for supporting the lower contracted face of the chimney, the middle portion of which is bulged outwardly, so as to 85 provide for the necessary expansion of the flame.

The fixed central - draft tube A' is provided at some distance below its upper edge with inwardly-projecting pins or studs f, which 90 support the base-ring F' of an inverted draft-cone, F. The draft-cone F is open at the top and bottom and attached by its contracted lower end to an interior seat, f', of the base-ring F'. Segmental openings f² are arranged 95 between the inner seat, f', and the outer circumference of the base-ring F', so as to permit a separate current of air to pass between the draft-tube A' and the interior draft-cone, F, in upward direction to the inner surface of 100 the flame, as shown by arrows in Fig. 2. The upper end of the draft-cone F is made flaring in outward direction, so as to direct the flame in connection with a deflector, G, of inverted

conical shape, which deflector is made of somewhat larger diameter than the upper edge of the draft-cone F and extended above the same, so as to cause the impingement of the 5 air-current which is drawn up at the interior of the draft-cone F on the upper part of the inner surface of the flame. The interior air-current is heated in its passage to the flame to a higher temperature than the air-current 10 which is drawn up in the annular channel formed between the draft-cone F and the fixed draft-tube A'. As the highly-heated air-current impinges on the inner surface of the flame at a point above the point of impingement of the less-heated air-current, that 15 passes in upward direction to the flame in the annular channel formed by the draft-cone and draft-tube, a more perfect combustion of the oil-vapors takes place, so that consequently, 20 in connection with the steady supply of air to the outer surface of the flame, a whiter flame and a better light are obtained.

The deflector G is provided at its lower end with a perforated socket, g, which is supported 25 on a shoulder, g', at the upper end of a spindle, G', which passes centrally through the draft-cone F, and is supported at its lower end in a central screw-eye, g², of a diametrical yoke, G², that is secured to the base-ring 30 F'. The yoke G² is preferably made of U shape and extended to some distance below the lower edge of the draft-cone F, so as to obstruct as little as possible the free upward passage of the air to the interior of the cone 35 F. The deflector G, the interior draft-cone, F, and the base-ring F', with its yoke G², can be readily removed from the supporting-studs f of the fixed draft-tube A', so as to be readily cleaned and replaced.

40 The fount A is provided around the supporting-neck A³ of the perforated cylinder E with a drip gutter or trough A⁴, which is shown in Fig. 2, and which serves to collect the oil that passes to the outside of the neck 45 by the so-called "sweating" of the lamp. The

oil thus collected in the drip-gutter A⁴ is gradually evaporated by the heating up of the neck of the fount, and the oil-vapors are drawn up and mingled with the upward current of air that passes through the perforated 50 cylinder-cone, so that they are fed to the flame and burned by the same.

The essential features of my improved lamp consist in the uniform air-supply to the outer surface of the flame by means of the perforated cylinder and the perforated distributing-ring of the gallery, and mainly of the interior detachable draft-cone and deflector, by means of which two separate air-currents of different temperatures are conducted to the 60 inner surface of the flame, so that a more perfect combustion of the oil-vapors at the inner surface takes place, which could not be attained in the same degree in the central-draft lamps, owing to the insufficient supply of 65 heated air to the inner surface of the flame.

Having thus described my invention, I claim as new and desire to secure by Letters Patent—

The combination, of a fixed central-draft tube, A', provided with inwardly-projecting 70 studs f, a base-ring, F', supported on said studs and provided with an interior seat, f', with segmental openings f², and with a diametrical U-shaped yoke, G², having a socket, g², a spindle, G', supported at its lower end 75 in said socket, and provided in its upper end with a shoulder, g', a draft-cone, F, supported on the interior seat of said base-ring, and a deflector, G, provided at its lower end with a perforated socket, g, which receives the upper 80 end of said spindle and rests on said shoulder thereof, substantially as described.

In testimony that I claim the foregoing as my invention I have signed my name in presence of two subscribing witnesses.

ALFRED O. BRUNNE.
